UNITED STATES PATENT OFFICE.

HENRY SCHOTT, OF LONGMEADOW, MASSACHUSETTS.

ICE-CREAM CUTTER.

Application filed March 1, 1922. Serial No. 540,186.

To all whom it may concern:

Be it known that I, HENRY SCHOTT, a citizen of the United States of America, and a resident of Longmeadow, in the county of 5 Hampden and State of Massachusetts, have invented a new and useful Ice-Cream Cutter, of which the following is a specification.

My invention relates to improvements in machines for cutting plastic or soft materials such as ice-cream, and consists essentially, with a suitable support or bed, of certain peculiarly restraining means, a plurality of vertically movable blades, and mechanism for operating said blades, all as 15 hereinafter set forth.

Heretofore much difficulty has been experienced in cutting slabs of material, such as ice-cream, into sections, pieces, or cakes of uniform size, work of this character having been done by hand, and requiring the services of a considerable number of operators, and the primary object of my invention is to overcome this difficulty, and dispense with a considerable proportion of 20 the operators, while at the same time producing expeditiously a greatly increased output. The cakes of ice-cream cut from a slab with this machine are accurate and uniform in their dimensions, and smooth and even on 25 all sides.

Another object is to produce a machine of the character described which consists of few parts, is simple in construction, is comparatively inexpensive, convenient to operate, and strong and durable.

Other objects and advantages will appear in the course of the following description.

I attain the objects and secure the advantages of my invention by the mechanism 40 illustrated in the accompanying drawings, in which—

Figure 1 is a front elevation of a machine or cutter which embodies a practical form of my invention, portions of the same being 45 broken away and in section; Fig. 2, a transverse, vertical section through said cutter, taken on lines 2—2, looking in the direction of the associated arrow, in Fig. 1, this view being on a smaller scale than the preceding 50 view; Fig. 3, an enlarged cross-section through one of the blade-holding bars and, Fig. 4 is a detail view of one of the cutting blades.

Similar characters of reference designate 55 similar parts throughout the several views.

In the present embodiment of the inven-

tion, the same comprises a bottom support or bed 1, a pair of hollow columns 3 mounted on said bed, a cross-bar 4 secured by bolts 26—26 to said columns, a plurality of restraining members 5 depending from said cross-bar, a blade-holder 6 supported at each end on a spring 7 in one of said columns, a plurality of blades 8 attached to said blade-holder, a pair of angular operating bars 9 for said blade-holder, and an operating lever 10 with which said bars are pivotally connected at 11, said lever being pivotally connected at 12 with a depending bracket 13. A cap or hood 14 may be provided for the 70 upper terminals of the restraining members 5.

The bed 1 may consist of the top of a bench, table, or of some other object, such as a slab or plate.

Each column 3 has a base 15 that is mounted on the bed 1 and secured thereto by means of screws 27—27. The upper portion of said column is vertically slotted through opposite sides, as represented at 80 16—16, such slots being in the longitudinal, vertical plane of the machine. The spring 7 in the column bears at the bottom on the base 15 of said column, and at the top supports a cross-bar 17, at one end thereof, 85 which cross-bar is below the cross-bar 4, extends through all of the slots 16, and forms a part of the blade-holder 6. The cross-bar 4 also extends through the slots 16.

The restraining members 5 are attached 90 at their upper terminals, by means of screws 18 and nuts 19, to the cross-bar 4, and said members are equi-distantly spaced. Each of the members 5 consists of a strip of sheet-metal bent into a generally triangular formation at the base and having upwardly-extending, parallel arms which embrace or extend both sides of the cross-bars 4 and 17, and are secured to the cross-bar 4 by means of the screws 18 and nuts 19. The base of 100 the triangular portion of each restraining member 5 is horizontal and located at the proper distance above the bed 1 to receive between it and said bed a slab of ice-cream of the required thickness. These restraining members prevent the cakes of ice-cream cut by the blades 8 from being upwardly displaced when said blades are elevated, and assist in holding said cakes after they are cut in place on the bed 1, besides initially 110 serving as position-indicating means for the said slab from which said cakes are cut.

The hood 14 is an open-bottom sheet-metal casing mounted on the cross-bar 4, and secured at each end thereto by means of a screw 20. The hood 14 extends downwardly far enough to cover the screws 18 and nuts 19.

The blade-holder 6 comprises, with the cross-bar 17, two pairs of oppositely-disposed, horizontal arms that turn downwardly at their outer terminals to form two pairs of oppositely-disposed, vertical arms, as best shown in Fig. 2. Connecting the aforesaid vertical arms on each side of the central, longitudinal, vertical plane of the machine, is a horizontal bar in which are set the blades 8. All of the parts of the blade-holder of which mention has just been made are integral. The blade-holder and blades may be said to constitute the knife 20 of the machine. In each bottom bar of the blade-holder 6 is a slot 21, which slot opens through the bottom of said member and also through the inner face of the same, as best shown in Fig. 3. These angular slots 21, 25 in the bottom or front and rear bars of the blade-holder 6, are oppositely-disposed, so that any slot in the rear bar is in the same plane with one of the slots in the front bar, and such plane is at right-angles to the central, vertical, plane of the cutter.

The blades 8 extend crosswise of the blade-holder 6 and the machine, and are received in the slots 21 in said holder. Each of the blades adjacent to each end thereof has a 35 notch 22 in the top edge to receive the lower portion of the bottom bar of the blade-holder 6 that assists in forming the slot 21, in which such end of said blade is located. The blades 8 are connected with the blade-holder from below, being driven into the 40 slots 21 in the bottom bars of said holder, with portions of said bars in the notches 22, the construction and arrangement of parts being such that the blades extend below the 45 blade-holder and project at both ends beyond the same, while the middle and wider portions of the blades extend upwardly in and through the narrow, vertical parts of the slots 21. The under edges of the blades 50 are ground to convert the blades into cutting implements.

Since the blades 8 are connected with the blade-holder 6 with a driving fit, any of said blades can be driven out of such engagement, by applying a hammer or other implement to one or both of the projecting ends of the blade, or to the upper edge of the same, wherefore it follows that it is a 55 comparatively simple and easy matter to remove and replace a blade. It is occasionally necessary to remove one or more blades for the purpose of sharpening the same, or in case of breakage or other damage, and subsequently to replace the same or another 60 blade or blades.

The cross-bar 17 is normally supported by the springs 7 at a height which retains the blade-holder 6 at a sufficient elevation to locate the blades 8 with their cutting edges above the under surfaces of the re- 70 straining members 5.

The cross-bar 17 extends through and beyond the slots 16 in the columns 3, and the operating bars 9 are connected with the protruding terminals of said cross-bar. 75 Each bar 9 has a vertical part in the upper terminal of which is a slot 23 to receive one terminal of the cross-bar 17. Transverse stop pins 24 are provided in the cross-bar 17 to assist in preventing said bar from 80 moving longitudinally, and the operating bars 9 from moving laterally, there being one of such pins between the slotted portion of each column 3 and the adjacent vertical part of one of the bars 9, another of such 85 pins on the side of such slotted portion that is opposite to the side thereof where said first-mentioned pin is located, and a third pin outside of said vertical part.

The vertical parts of the operating bars 9 extend downwardly from the cross-bar 17 through openings 24-24 in the bed 1, and converge below said bed to meet the operating lever 10. Thus it is seen that the bars 9 consist of vertical and oblique parts, the 95 inner terminals of which latter are pivoted at 11 to the lever 10 intermediate of the ends thereof.

The bracket 13 depends from the underside of the bed 1, and the rear terminal of 100 the lever 10 is pivoted at 12 to the lower terminal of said bracket. The lever 10 extends forwardly some distance in front of the pivot 11.

When the knife is held by the spring 7 in 105 normal position, the lever 10 is disposed, by the intervening parts and members, at an upward and forward incline from the pivot 12. Upon grasping the forward terminal of the lever 10 and forcing the same downwardly, 110 said lever swinging on the pivot 12, the operating bars 9 are actuated downwardly by said lever, and carry with them, against the resiliency of the springs 7, the cross-bar 17 and the other members of the blade-holder 115 6, together with the blades 8. The amount of downward movement obtainable by this means and in this manner is sufficient to carry the blades 8 down onto the bed 1. Upon releasing the lever 10, the springs 7 120 immediately act to elevate the blade-holder 6 and connected parts and members, thus restoring them to normal position and swinging said lever upwardly into its former or initial position.

The cross-bar 17 is prevented from rocking during the operation of the same by the sides of the slots 16, but there is sufficient looseness of parts and lost motion between the bars 9 and said cross-bar and 130

in the openings 24 to permit the mechanism to be actuated by the lever 10.

In practice, assuming that a slab of ice-cream be placed on the bed 1 beneath the 5 restraining members 5, and that such slab be of a length equal to the distance from the outside edge of the restraining member at one end of the group to the outside edge of the other end restraining member, and of 10 a width which is less than the distance between the bottom bars of the blade-holder 6, and be located with the ends of the slab flush with the outer edges of said end restraining members, and within the vertical 15 planes of said bars, the lever 10 is depressed to actuate said blade-holder downwardly and force the blades 8 through said slab from top to bottom, and then said lever is released and said blades are withdrawn and carried 20 upwardly above the horizontal plane of the top of the ice-cream. Where there was a single slab of ice-cream there are now nine cakes of equal dimensions and smooth and even sides. These bars of ice-cream are 25 now removed from the bed 1 and another slab placed thereon for a repetition of the cutting operation.

Nine cakes of ice-cream are cut at each 30 operation because there are nine restraining members 5 and eight blades 8. These numbers may, of course, be varied.

More or less change in the size, shape, construction, and arrangement of some or all of the parts of this may be made without violating the spirit of my invention or exceeding 35 the scope of what is claimed.

What I claim as my invention, and desire to secure by Letters Patent, is—

1. The combination, in a cutter of the class 40 described, with a support, members rising above said support, a cross bar attached to said members and a plurality of restraining members supported in spaced relationship from said bar, each of said restraining members 45 consisting of a strip of sheet-metal bent into a generally triangular form at the base and extending upwardly to be secured to said bar, of a blade-holder provided with a plurality of blades receivable in the spaces 50 between said restraining members, and mechanism to actuate said blade-holder to cause said blades to cut through material on said support beneath said restraining members.

55 2. The combination, in a cutter of the class described, with a support, a pair of hollow slotted columns, springs in said columns, a cross bar attached to said columns at the top, and restraining members depending 60 from said bar, said members being in spaced relationship, of a blade-holder having parts that extend through the slots in said columns and rest on said springs, a plurality of blades attached to said blade-holder, said 65 blades being arranged and adapted to operate

in the spaces between said restraining members, and mechanism to actuate said blade-holder against the resiliency of said springs to cause said blades to cut through material on said support beneath said restraining 70 members.

3. The combination, in a cutter of the class described, with a support, hollow slotted columns extending above said support, springs in said columns, a cross bar attached to said columns, and depending restraining members attached to said bar, said restraining members being in spaced relationship, of a blade-holder comprising a cross bar that extends above the base portions of said restraining members and into the slots in said columns and rests on the springs therein, arms that extend outwardly and downwardly from opposite sides of said second-named cross-bar, and bars connecting said arms at 80 their bases respectively in front of and behind said restraining members, a plurality of blades attached to said last-named bars and arranged and adapted to operate in the spaces between said restraining members, an 85 operating lever pivotally connected at one end, and connecting members between the aforesaid parts of said blade-holder and said lever.

4. The combination, in a cutter of the class 90 described, with a support, and restraining means above said support for material on the same, said restraining means consisting in part of spaced elements, of an upwardly spring-pressed blade-holder comprising 100 front and back arms connected at their lower ends with front and back bars, said bars being respectively in front of and behind said spaced elements, a plurality of knives attached to said bars and arranged and adapted to operate between said elements, and mechanism to actuate said blade-holder against the resiliency of the springs to cause 105 said blades to cut through said material.

5. The combination, in a cutter of the class 110 described, with a bed, hollow slotted columns mounted on said bed, springs in said columns, a cross-bar attached to said columns, and restraining members depending from said cross-bar and being in spaced relationship, of a blade-holder comprising a cross-bar which is below said first-named cross-bar, extends through the slots in said columns, and rests on said springs, and front 115 and back arms connected at their lower ends with front and back bars which are outside of said restraining members, a plurality of knives attached to said last-named bars and arranged and adapted to operate between said restraining members, and mechanism to 120 actuate said blade-holder against the resiliency of said springs to cause said blades to cut through material on said bed beneath said restraining members.

6. In a cutter of the class described, a 130

- movable blade-holder consisting in part of parallel bars having angular slots in their bottom edges and inner sides, with the portions of the slots that are in the inner sides 5 of said bars extending only part way through the thickness of the same and opening at the bottom into the portions of the slots that are in the under edges of the bars, and blades receivable in said slots.
- 10 7. In a cutter of the class described, a blade-holder consisting in part of parallel bars having angular slots in their under edges and inner sides, with the portions of the slots that are in the inner sides of said 15 bars extending only part way through the thickness of the same and opening at the bottom into the portions of the slots that are in the under edges of the bars, and blades receivable in said slots and having notches 20 therein to receive the bottom edges of the slotted parts of said bars.
8. The combination, in a cutter of the class described, with a bed, slotted hollow columns mounted on said bed, springs in said 25 columns, a cross-bar attached to said columns, restraining members depending from said cross-bar and being in spaced relationship, and a bracket depending from said bed, of a blade-holder comprising a cross-bar below said first-named cross-bar, extending 30 through the slots in said columns and beyond the latter, and resting on said springs, arms extending from both sides of said second-named cross-bar and extending downwardly, 35 and front and rear bars connecting said arms at their lower terminals, a plurality of blades, attached to said front and rear bars and arranged and adapted to operate in the spaces

between said restraining members, a lever pivotally connected with said bracket, and 40 operating bars extending downwardly from said second-named cross-bar and having their lower terminals pivotally connected with said lever.

9. The combination, in a cutter of the class 45 described, with a bed, slotted hollow columns mounted on said bed, springs in said columns, a cross-bar attached to said columns, restraining members depending from said cross-bars and being in spaced relationship, and a bracket depending from said bed, of a blade-holder comprising a cross-bar below 50 said first-named cross-bar, extending through the slots in said columns and beyond the latter, and resting on said springs, arms 55 extending from both sides of said second-named cross-bar and extending downwardly, and front and rear bars connecting said arms at their lower terminals, a plurality of blades attached to said front and rear bars and ar- 60 ranged and adapted to operate in the spaces between said restraining members, a lever pivotally connected with said bracket, op- 65 erating bars extending downwardly from said second-named cross-bar and having their lower terminals pivotally connected with said lever, and pins in said second-named cross-bar, said pins being arranged and adapted to hold the cross-bar against longitudinal movement in said slots, and to 70 hold said operating bars against lateral movement on the cross-bar.

HENRY SCHOTT.
